UNITED STATES PATENT OFFICE.

HECTOR V. LOUGH, OF HARTFORD, CONNECTICUT, ASSIGNOR TO LOUGH BROTHERS,
A PARTNERSHIP CONSISTING OF WALTER E. LOUGH AND PERCY F. LOUGH, OF
NEW YORK, N. Y.

FAUCET.

Application filed April 15, 1924. Serial No. 706,633.

To all whom it may concern:

Be it known that I, HECTOR V. LOUGH, a subject of the King of Great Britain, and resident of Hartford, in the county of Hartford 5 and State of Connecticut, have invented certain new and useful Improvements in Faucets, of which the following is a specification.

The invention relates to improvements in 10 faucets and more particularly to quick-opening faucets adapted to be used in connection with oil barrels or the like, or as a molasses gate, etc.

An object of the invention is the provision 15 of a device of the character referred to which shall be simple, durable and comparatively inexpensive to produce, which may be easily and quickly operated and in which the faucet or passageway may be quickly opened 20 or closed by movement of a hand lever from one position to another. Another object of the invention is to provide a device of the character referred to in which the opening is positively closed by an improved form 25 of toggle action when the hand lever is swung into one of its extreme positions.

In the preferred form of the invention the hand lever is pivotally mounted on a sleeve 30 slidably mounted on the fixed tube of the construction, the sleeve having a closed end with a seat therein adapted to bear against the end of the tube to firmly close the delivery opening when the sleeve is in its innermost position. The hand lever is connected to the fixed tube by a pair of links 35 so arranged as to cause the sliding movement of the sleeve as the hand lever is swung in one direction or the other and to cause the positive closing of the end of the tube by a toggle action when the hand lever is 40 swung down into its closing position. The link or links referred to are preferably given a springy construction, and are so arranged as to exert spring pressure upon the coacting parts when the opening is closed. When the hand lever is swung downwardly 45 to draw in the sleeve and close the end of the tube, the links will come into approximate alignment with the pivotal center of the hand lever at the moment when the seat in the sleeve engages the end of the tube.

A further movement of the hand lever results in springing the links beyond the plane 50 in which the pivot of the lever is located

so as to force the end of the tube and the 55 seat in the sleeve together under spring pressure. By this means a tight closure is insured regardless of any slight inaccuracies of adjustment or wear, etc.

The invention consists in the improved 60 faucet construction more fully set forth in the following specification, according to a preferred embodiment thereof. Other objects of the invention consist in the provision of improved combinations of parts and elements of construction, all as will be more fully set forth in the following specification, and be particularly pointed out in the appended claims.

In order that the invention may be more 70 clearly understood attention is hereby directed to the accompanying drawings, forming part of this application and illustrating one embodiment of the invention. In the drawings,

Fig. 1 is a side elevation of a quick acting barrel faucet construction, the hand lever being in its lowermost position, in which the opening is closed;

Fig. 2 is a longitudinal section through 80 the device, the hand lever being raised to effect the opening;

Fig. 3 is an end view of the faucet construction shown in Fig. 1, and

Fig. 4 is a side elevation of the construction 85 showing the position of the hand lever at the moment when the end of the tube first engages its seat in the sleeve.

Referring to the drawings, the open ended tube 1 of suitable metal is shown as provided with a screw-threaded end 2 adapted to be screwed into a threaded bung opening of an oil barrel or the like, the tube being illustrated as provided with a peripheral angular shoulder 3 which may be used as a wrench to screw the threaded tube 2 into place. The thread on tube 2 is tapered to make a tight fit, as in pipe fittings. Lugs 4 are provided to extend forwardly from peripheral shoulder 3, one on each side of 90 the device.

The sleeve 5 is slidably mounted on the forwardly extending tube 1, this sleeve having a closed front end 6 and a downwardly extending discharge spout 7, opening into 105 the sleeve immediately to the rear of the closed front end 6. The tube or conduit 1, as it extends forwardly from shoulder

3, is preferably circular in cross section, and the sleeve 5 has a suitable bore to slidably fit thereon, the exterior of the sleeve having, however, a polygonal shape in cross-section, with straight vertical sides 5¹, as is indicated in Fig. 3. The side portions of the sleeve are cut away somewhat at the rear, as is indicated at 8 in Fig. 2, to form recesses which will fit about the lugs 4 on shoulder 3 when the sleeve is in its rearmost position, shown in Fig. 1.

The hand lever is preferably a bifurcated member which may conveniently be pressed to form of sheet metal. The hand lever 15 comprises a pair of arms, 9, 9, pivotally connected to the opposite sides of sleeve 5 by studs 10. Arms 9 extend parallel to the vertical sides 5¹ of sleeve 5. The upper or free ends of arms 9 of the hand lever are connected together by a transverse portion 11 which extends above the top of sleeve 5 and forwardly beyond the front end of the same when the construction is in its closed position, shown in Fig. 1. This transverse portion 25 11 of the hand lever stiffens the lever and provides a convenient handle. When the faucet is to be opened the forwardly extending portion 11 of the lever is grasped and swung upwardly into the position shown in Fig. 2.

The lever is connected to the fixed tube 1 by the spring links 12, 12, one on each side of the device and preferably mounted between the arms 9 of the hand lever and the 35 adjacent side surfaces 5¹ of the sleeve. The links are pivotally connected at their rear ends to lugs 4 on shoulder 3 of the tube as indicated at 13, the forward ends of the links being pivotally connected to arms 9 40 of the hand lever, as is indicated at 14.

Links 12 are preferably formed of spring steel and are preferably each given a reverse curve, as shown. When the hand lever is 45 swung back from the position shown in Fig. 1 to the position shown in Fig. 2, the link connection between the tube and hand lever serves to push the sleeve forwardly over the tube so as to unseat the end 15 of the tube from the packing ring 16 which preferably 50 is provided within the closed end 6 of the tube. This effects a quick opening of the device and fluid will flow through the end of tube 1 and out through the spout 7 in the sleeve.

55 When the connection is to be closed the hand lever is swung forwardly by handle portion 11, the sleeve and the pivotal connection 10 of the hand lever necessarily sliding inwardly over the tube. A comparatively 60 short movement of the hand lever from the Fig. 2 position to the Fig. 4 position suffices to bring the end 15 of the tube into contact with the packing 16 in the closed end of the sleeve. At this time the pivotal connection 14 of the links with the arms 9 of

the lever has dropped down almost into the horizontal plane in which are located the pivots 10 of the lever and the rear connection 13 of the links. The further downward movement of the lever into the Fig. 1 position forces the links 12 down into the position shown in Fig. 1, in which the forward ends 14 of the links are somewhat below the horizontal plane in which are located the pivotal connections 10 of the lever and 13 of the links. This movement is permitted by the springiness of the links and results in forcing the end of the tube firmly into engagement with packing 16, as stated. This movement also results in locking the parts 70 firmly in closed position, with the bail or transverse portion 11 of the lever resting against the top of the sleeve. When now the faucet or valve is again to be opened upward pressure on bail 11 carries the connection 14 of the links above the horizontal center, whereupon the springiness of the links will aid in the continued opening movement of the lever. The movement of the lever from its Fig. 4 position to its Fig. 2 80 position suffices to entirely open the connection between the tube and spout 7 effecting the quick opening of the device.

The construction may be provided with a lock to prevent opening of the faucet by the 85 hand lever when desired. As shown, the sleeve has a lug 17 formed thereon with an opening 18 therethrough, through which the hasp 19 of a padlock may be inserted to lock the lever in its bottom position. When this 90 construction is used the rear edge portion of the bail 11 of the hand lever is cut away sufficiently to permit movement of the same down over the lug 17. When the padlock is in position, as is shown in Fig. 1, it is, of course, impossible to raise the hand lever, or to raise the same sufficiently to unseat the end 15 of the tube.

It will be noted that in the construction described the links 12 and the portion of the 100 hand lever extending between connection 14 of the links and pivot 10 of the lever constitute the arms of a toggle joint. Also that a particularly quick-acting device is provided by the construction described in 110 which the opening and closing are effected by the sliding movement of the pivot of the lever as well as by the rotation of the lever about its pivot.

It should be understood that the invention 115 is not limited strictly to the details of construction which have been particularly described, but that the same is as broad as is indicated by the accompanying claims.

120 What I claim is:

1. In a faucet, the combination of an open ended tube, a sleeve mounted thereon having a closed end adapted to seat against the outer end of said tube to close the same, said sleeve having a lateral discharge open- 125 130

ing therethrough adjacent to its outer end, a hand lever pivotally connected to said sleeve, and a spring link pivotally connecting said tube and lever, so arranged as to move said sleeve to closed or open position as said lever is moved in one direction or the other and to be placed under stress in a position such as to press the sleeve against the end of the tube, when said sleeve seats against the end of said tube.

2. In a faucet, the combination of an open ended tube, adapted to be fixed in position, a sleeve slidably mounted thereon, having a closed end adapted to seat against the outer end of said tube to close the same, said sleeve having a lateral discharge opening therethrough adjacent to its outer end, a hand lever pivotally connected at one end to said sleeve, adapted to swing over a surface thereof closely adjacent thereto, from a lower to a raised position, and a link pivotally connected at its ends to said tube and hand lever, so arranged as to hold the closed end of said sleeve in firm contact with the end of said tube when the lever is in one position, and to cause the movement of said sleeve outwardly on said tube, to open the end thereof, when the lever is swung to its opposite position.

3. In a faucet, the combination of an open ended tube, a sleeve mounted thereon having a closed end adapted to seat against the outer end of said tube to close the same, said sleeve having a lateral discharge opening therethrough adjacent to its outer end, a hand lever pivotally connected adjacent one end to said sleeve, and a curved metal link connected at one end to said tube to the rear of the pivot of said lever, in the approximate horizontal plane thereof, and at its other end to a point on said lever which moves from above the pivot of the lever to a position in front of and below said pivot, as the lever descends and the tube end seats against the closed sleeve end.

4. In a faucet, the combination of an open ended tube, adapted to be fixed in position, a sleeve slidably mounted thereon having a closed end adapted to seat against the outer end of said tube to close the same, said sleeve having a lateral discharge opening therethrough adjacent to its outer end, a hand lever comprising parallel arms pivoted to opposite sides of said sleeve, extending upwardly and connected by a trans-

verse handle portion adapted to rest against the top of said sleeve when the tube end and sleeve are seated together in closed position, and forwardly extending curved links, connecting points on said tube at the rear of the pivots of said hand lever arms to points on said arms which move from above said pivots to positions in front of and below said pivots as the lever descends in seating the tube end and sleeve end together.

5. In a faucet, the combination of an open ended tube, adapted to be fixed in position, a sleeve slidably mounted thereon having a closed end adapted to seat against the outer end of said tube to close the same, said sleeve having a lateral discharge opening therethrough adjacent to its outer end, a hand lever pivotally connected at one end to said sleeve, adapted to swing over a surface thereof closely adjacent thereto, from a lower to a raised position, and a link pivotally connected at its ends to said tube and hand lever, so arranged as to form a toggle joint with said lever, to align and hold the closed end of said sleeve in contact with the end of said tube when the lever is in lower position, and means for locking the lever against movement from said lower position.

6. In a faucet, the combination of an open ended tube, adapted to be fixed in position, a sleeve slidably mounted thereon having a closed end adapted to seat against the outer end of said tube to close the same, said sleeve having a lateral discharge opening therethrough adjacent to its outer end, a hand lever pivoted to said sleeve, to move forward and back with said sleeve and to swing about its pivot from an upper position to a lower position, said sleeve having a surface against which said lever seats in its lower position, and a resilient link connecting said tube and lever at such points as to constitute a toggle with said lever, and to cause a limited movement of said lever downwards to close said tube and sleeve ends together, and a further movement of said lever to its lower seated position to swing said link past the pivot of said lever, to spring said link and resiliently press said tube and sleeve ends together.

In testimony whereof I have signed my name to this specification.

HECTOR V. LOUGH.
